UNITED STATES PATENT OFFICE.

OSCAR E. DRAKE, OF HAVRE, MONTANA.

WASHBOARD.

1,279,092.

Specification of Letters Patent. Patented Sept. 17, 1918.

Application filed March 20, 1915. Serial No. 15,742.

To all whom it may concern:

Be it known that I, OSCAR E. DRAKE, a citizen of the United States, residing at Havre, in the county of Hill and State of Montana, have invented a new and useful Washboard; and I do hereby declare the following to be a full, clear, and exact description of the invention, such as will enable others skilled in the art to which it appertains to make and use the same.

This invention relates to the art of laundry, and particularly to a new and useful rub board for a wash board, and more especially to the connection between the two.

One of the objects of the invention is the provision of improved connecting means between the rub board and the wash board, whereby the rub board at each end of its stroke may be thrown closer to the rubbing surface or rubbing rollers of the wash board, than when the rub board is passing over the central portion of the rubbing rollers of the wash board. In other words, when the rub board is reciprocated it also receives a variable movement toward and from the rubbing rollers of the wash board. Furthermore, during the reciprocatory movement of the rub board, the same moves substantially in a parallel plane with the wash board during a portion of said movement, through the medium of said improved connection.

In practical fields the details of construction may necessitate alterations, falling within the scope of what is claimed.

The invention comprises further features and combination of parts, as hereinafter set forth, shown in the drawings and claimed.

In the drawings:

Figure 1 is a front elevation of the improved wash and rub boards and their connections constructed in accordance with the invention, showing the rub board in its lowermost position.

Fig. 2 is a sectional view on line 2-2 of Fig. 1.

Fig. 3 is a view similar to Fig. 2 showing the rub board in its uppermost position.

Fig. 4 is a rear elevation showing the rub board in its lowermost position, thereby showing the position of the parts of the connections between the rub and wash boards.

Fig. 5 is a rear elevation showing the rub board in its uppermost position, thereby

illustrating the positions of the part of said connections.

Fig. 6 is a sectional view showing an intermediate position of the rub board.

Fig. 7 is an enlarged detail view of the connections between the rub and wash boards.

Fig. 8 is a detail sectional view showing the mounting and bearings of one of the rollers 13 and one of the pintles 12.

Fig. 9 is a detail view in elevation of the link block 24.

Fig. 10 is a detail view in elevation of the link block 23.

Referring more especially to the drawings, 1 and 2 designate the side rails of the wash board, the inner faces of which are provided with longitudinal grooves 3, and the upper ends of said side rails are connected by the transverse bars 4. Secured in the upper portions of said grooves are the opposite ends of a board 5, which also connects the side rails. Secured to the board 5 are the upper and lower strips 7 and 8, the lower strip 8 acting to support the soap and the like. Therefore the board 5 and its strips constitute a holder. Pivoted at 9 and 10 to the upper and lower strips is a heavy wire bracket 11, which may be thrown as shown in the sectional views to engage the peripheral edge of a wash tub, and when the wash board is not in use, this bracket may be thrown flat against the board 5.

Journaled in suitable bearings of the side rails are the pintles 12 of the plurality of rubbing rollers 13, which are slightly spaced apart as shown to permit the suds to pass between the rollers back into the tub. The rub board 15 comprises the side rails 16, the handle 17 (which connects the upper ends of the rails 16) and the board 18 (the ends of which are secured to the side rails 16 as at 19) and one face of the board 18 is provided with a corrugated surface 20, which co-operates with the rollers in rubbing the clothes. A transverse rod bracket 21 has its downwardly extending end 22 securely fastened in the lower portions of the grooves of the inner faces of the rails 1 and 2. This rod bracket is provided with a rearwardly extending but transversely disposed angle portion 22^a, on which a link block 23 is pivoted, and also pivoted upon the rod bracket adjacent the inner faces of

the rails 1 and 2 are link blocks 24. Extending through the link blocks 24 loosely is a rod 25, the right angled ends 26 of which are pivotally connected at 27 to the lower ends of the side rails 16 of the rub board. By extending the rod 25 loosely through the link blocks 24 it will be seen that said blocks 24 have loose pivotal connections with the rod. The rod 25 is formed with an arched portion 28, which is loosely pivoted in the link block 23. Also loosely pivoted at 29 in the blocks 24 are the ends 30 of the rocking rod 31, which is provided with an arch part 32, which is pivoted in the link block 23. 10 The link block 23 comprises two sections, the central section 33, and the cap or cover section 34. However, the cover sections are integrally connected at 35, and between these cover sections, the central triangular section 33 fits, thereby in this manner pivotally connecting the link block 23 to the various rods. The link blocks 24 consist of two parts 40 and 41, so that they may be pivotally connected to the rod 25 and the rod bracket. It 15 is to be noted that by the particular construction and the disposition of the rod bracket and the oscillating rod, the rub board during a portion of its reciprocatory movement will move substantially parallel to the rubbing rollers of the wash board, and when the rub board is in the act of reaching each end of its reciprocatory movement it will move toward the rubbing rollers of the wash board. Therefore the side rails 1 and 2 of the 20 wash board are provided with guides 43^a of the shape to correspond with the movement of the rub board. The guides 43^a act to steady the rub board during its reciprocating movement, and to hold the same substantially 25 parallel to the rubbing rollers for a portion of its reciprocating movement. The side rails 16 of the rub board have projections 43 to ride upon the guides 43^a, to hold the rub board substantially true to its parallel

movement with relation to the wash board 45 during a portion of the reciprocating movement of the rub board.

The invention having been set forth, what is claimed as new and useful is:—

The combination with a wash board frame 50 having side rails and provided with a rubbing surface supported by said side rails, of a rub board having a corrugated rubbing surface to coöperate with the first rubbing surface, said rub board having right angle 55 projections extending toward the front edges of the side rails of the wash board frame, said rub board having its side rails in spaced parallelism with and alined over the front edges of the side rails of the wash board 60 frame, whereby said right angle projections may extend toward, engage and guide slidably and fulcrum on the front edges of the side rails of the wash board frame, to hold the rub board substantially parallel with the 65 rubbing surface of said wash board frame during the reciprocating movement of the rub board, said rub board having swinging arms extending below the side rails of the frame, swinging links connecting between 70 the extended ends of said arms and the frame, and supporting and governing rods for said links, whereby said rub board, upon reaching one end of each of its strokes, will crush and rinse the clothes against the rubbing surface of the wash board frame, and whereby a slight rising and falling movement may be imparted to one end of the rub board, since the right angle projections fulcrum on the front edges of the side rails of 75 80 the wash board frame.

In testimony whereof I have signed my name to this specification in the presence of two subscribing witnesses.

OSCAR E. DRAKE.
